UNITED STATES PATENT OFFICE

WILLIAM H. KITTO, OF CANTON, OHIO, ASSIGNOR TO THE HOOVER COMPANY, OF
NORTH CANTON, OHIO, A CORPORATION OF OHIO

SUCTION CLEANER

Application filed May 28, 1930. Serial No. 456,385.

This invention relates to suction cleaners and particularly to improvements therein through the provision of air-flow-directing means and novel agitating means in cooperation therewith. The invention has for its object the provision of a suction cleaner of simplicity and efficiency; the provision of new and novel agitating means; the provision of a construction in which the point of air 5 cleaning effectiveness and the point of positive agitation substantially coincide; the provision within the suction nozzle of a body containing air at atmospheric pressure in combination with separate agitating means 10 within said nozzle. Other and more specific objects will appear upon reading the specification and considering therewith the drawings annexed.

Referring now to the drawings in which is disclosed a preferred embodiment of the present invention:

Fig. 1 discloses a side view of a suction cleaner constructed in accordance with the present invention, with certain parts broken 25 away;

Fig. 2 is a front view of a suction cleaner constructed in accordance with the present invention with certain parts removed and broken away.

Like reference characters identify similar parts in the various views.

The suction cleaner constructed in accordance with the present invention comprises the usual parts of a suction cleaner including 35 the motor casing 1, which houses the driving motor which is not shown; the fan casing 2 forming the fan chamber 3, within which is positioned the fan 4 carried by the extended motor shaft 5; and the nozzle 6 which is 40 carried by the forward face of the fan casing 2 and opens directly thereto at the eye 7 of the fan chamber. Carried by the forward face of the nozzle 6, and serving to close the opening 8 therein, is the removable cover 45 plate 9. Front supporting wheels 10, 10 and a rear supporting wheel 11 support the cleaner on the surface covering and a handle bail 12, which is pivoted to the motor casing, is connected to a handle, which is not shown, and 50 provides means by which the cleaner may be

propelled. The aforescribed parts comprise the usual suction cleaner and no invention resides in the construction thereof, broadly.

Positioned within the nozzle 6 and extending the length thereof is a substantially cylindrical member 13 which is supported at each end upon the flange 14 of the removable end plate 15 of the suction cleaner nozzle. Securing means, such as screws 16 and 17, secure the inner member to the end plate and the end plate to the suction cleaner, respectively. Member 13 within the nozzle 6 is in effect an air tunnel which is opened at each end to the atmospheric pressure through an opening 18 provided in the end plate 15, and which is itself opened along its bottom between the edges 19 and 20, which are in effect penetrating lips as will be more clearly disclosed as the specification proceeds. Positioned centrally of the member 13 and secured thereto is the housing member 21 which opens interiorly into the member 13 and, in effect, provides an offset channel 22 therefor. Securing means 23, 23 etc., are provided to secure the housing 21 to the member 13. Positioned upon the nozzle 6 are lips 24 and 25 which, as distinguished from the penetrating lips 19 and 20 of the interior member or tunnel 13, are very broad. These lips are provided with an upward and inwardly curved surfaces which conform to the contour of the displaced surface covering with which they contact in the operation of the machine so that very little of the air drawn 85 into the nozzle, in response to the vacuum created therein by the suction fan, will enter between these broad sealing lips and the surface covering.

Positioned within the interior of the air tunnel 13 with its lower edge extending between the penetrating lips 19 and 20 thereof is the agitating member or finger 26 which is supported at each of its ends by a supporting arm 27 which is rotatably mounted within a bearing 28 in the removable end plate 15 of the nozzle 6. The agitating member 26 is provided along its lower or surface-contacting edge with a smooth hardened metallic covering 29 which prevents injury to the sur- 90 95 100

face covering. Extending laterally from the central portion of the agitating member 26 into the offset channel 22 from the air tunnel 13 is an arm 30 which is provided with a 5 forked end having an extended slot 31. Positioned vertically within the channel 22 with its reduced end extending between the spaced ends of the arm 30 is the driving shaft 32 which is provided at its lower end with a 10 pin 33 which is positioned within the slot 31 in the arm 30. Shaft 32 extends upwardly through the housing 21 at the opening 34 which is provided with an air-seal washer 35 which is maintained in position by an out- 15 standing portion 36 of the forward wall of the fan casing 2, said offset portion being provided with an opening 37 which provides a sliding bearing for the shaft 32. Drive shaft 32 is forked at its upper end and re- 20 ceives the downwardly extending projection of member 38 which is carried by the bearing 39 mounted on the pin 40 which is itself carried by the circular plate 41 eccentrically of the motor shaft 5.

25 As the motor revolves, in the operation of the cleaner, the eccentrically mounted pin 40 revolves in its orbit about the motor shaft 5 carrying with it the member 38 which is pivoted at its projecting portion to the drive shaft 32 by the pin 42. The drive shaft 32 receives a vertical reciprocating motion the extent of which is determined by the eccentricity of pin 40 with respect to the shaft 5 of the motor. As the lower end of the drive 30 shaft 32 reciprocates up and down it carries with it projecting arm 30 of the agitating member 26, the sliding of the pin 33 in the slot 31 permitting relative movement between said drive shaft 32 and said arm 30 35 caused by the arcuate movement of said arm. The result of the arm 30 being carried alternately up and down by the drive shaft 32 is the pivoting of the agitating member 26 upon its supports 27, 27 in the bearings 28, 40 45 28 and the alternate arcuate movement of the lower edge of said member between the penetrating lips 19 and 20 of the air tunnel 13.

In the operation of the cleaner constructed in accordance with the present invention the 50 suction fan 4, being driven by the driving motor, creates a reduced pressure within the suction nozzle 6 through the exhaustion of the air therefrom. The surface covering, over which the cleaner is passing, is lifted upward into the nozzle until it contacts the broad sealing lips 24 and 25. Lips 24 and 25 function, because of their relatively great width, to provide an excellent seal with the covering and to maintain it in the lifted position 55 60 65 and, while preventing the leakage of an appreciable quantity of air therebetween, offer a minimum resistance to the sliding of the nozzle relative thereto. As the air is unable to gain entrance into the nozzle 6 by means of the customary entrance under the nozzle

70 lips it seeks the path of least resistance and enters said nozzle by passing under the penetrating lips 19 and 20, the air in the air tunnel 13 being at substantially atmospheric pressure as openings 18, 18 are provided at the ends thereof. The penetrating lips 19 and 20 which contact the uplifted, and consequently bowed section of the surface covering, function, because of their extremely small width, to separate the adjacent rows 75 of pile and the adjacent tufts of a single row of pile of said surface covering and to provide for the air which passes thereunder, on its way into the main nozzle 6, an open pathway to the empacked, embedded foreign particles at the base of the surface covering. The positively actuated agitating member 26, within the air tunnel 13, contacts the surface covering between the penetrating lips thereof and agitates, flexes and bends the pile resulting in the dislodgment of all foreign particles and the making possible of their removal by the cleaning air which passes under the lips 19 and 20 as said lips pass over the point which has been agitated by said agitating member.

80 The invention combines in a new and novel construction a combination of broad sealing lips, which make possible the use of high vacuum without increasing the resistance to 85 movement of the cleaner, and penetrating lips which make possible the entrance of the cleaning air to the embedded foreign particles in the surface covering undergoing cleaning, and lastly, a positive agitating member 90 which functions to dislodge all foreign particles embedded in the surface covering making possible their removal by the cleaning air.

95 Having clearly set forth and described my invention, I claim:

100 1. In a suction cleaner, a suction nozzle adapted to contact a surface covering undergoing cleaning, means to create a reduced pressure in said nozzle, a member having a downwardly facing opening within said nozzle 105 interiorly connected to air at atmospheric pressure, reciprocating agitating means within said nozzle, and means to positively actuate said agitating means.

110 2. In a suction cleaner a suction nozzle adapted to contact a surface covering undergoing cleaning, means to create a reduced pressure in said nozzle, a member open to and within said nozzle interiorly connected with the atmosphere, means comprising penetrating lips directing the flow of air from the point of high pressure to the point of low pressure into the surface covering undergoing cleaning, reciprocating agitating means within said nozzle and means to positively 115 actuate said agitating means.

120 3. In a suction cleaner a suction nozzle adapted to contact a surface covering undergoing cleaning, means to create a reduced pressure in said nozzle, a member open to and 125 130

within said nozzle interiorly connected to the atmosphere, means directing the flow of air from the point of high pressure to the point of low pressure into the surface covering,
5 agitating means within said nozzle, and means to impart an alternate rotary movement to said agitating means.

4. In a suction cleaner a suction nozzle, means to create a reduced pressure in said
10 nozzle, a member open to and within said nozzle interiorly connected to atmosphere, means directing the flow of air from the point of high pressure to the point of low pressure into a surface covering below the nozzle, agi-
15 tating means within said nozzle comprising an agitating finger, and means to impart an alternate rotary movement to said agitating means.

5. In a suction cleaner a suction nozzle, an
20 air tunnel within said suction nozzle interiorly connected to atmosphere and having a downwardly facing opening, lips upon said air tunnel adapted to contact the surface covering undergoing cleaning, reciprocating
25 agitating means within said air tunnel, and means to positively actuate said agitating means.

6. In a suction cleaner a suction nozzle, an air tunnel within said suction nozzle interiorly connected with the atmosphere, surface contacting lips upon said air tunnel defining a downwardly facing opening, alternate rotary agitating means positioned within said air tunnel, and means to positively
35 actuate said agitating means.

7. In a suction cleaner a suction nozzle, a broad sealing lip upon said nozzle, an air tunnel open along its lower side within said nozzle interiorly connected to the atmosphere,
40 an agitating finger within said nozzle, and means to positively actuate said finger.

Signed at North Canton, in the county of Stark, and State of Ohio, this 14th day of May, A. D., 1930.

45 WILLIAM H. KITTO.
